UNITED STATES PATENT OFFICE

1,924,467

INTERNAL COMBUSTION ENGINE

Joseph Edward Smith, Crescent City, Calif.

Application October 30, 1930. Serial No. 492,273

1 Claim. (Cl. 123—59)

This invention relates to new and useful improvements in internal combustion engines and more particularly to a novel valve structure.

The principal object of this invention is to provide a valve for internal combustion engines which will not require re-grinding or reseating as is the case with the present type of poppet valve now used in automobile engines.

Another important object of the invention is to provide a rotary type of valve wherein the valve will always be maintained equalized against side lashing.

Other important objects and advantages of the invention will become apparent to the reader of the following specification.

In the drawings:—

Figure 1 represents a top plan view of the novel engine.

Fig. 2 represents a longitudinal sectional view through the novel valve structure.

Fig. 3 represents a sectional view taken substantially on the line 3—3 of Fig. 1.

Fig. 4 represents a bottom plan view of the engine head structure.

Referring to the drawings wherein like numerals designate like parts, it can be seen in Fig. 3, that numeral 5 represents the cylinder block with any number of cylinder bores 6 therein.

This cylinder block 5 is provided with a narrow flange 7 at one side and a relatively wide flange 8 at its opposite side. Numeral 9 represents a head structure and numeral 10 represents a cap structure. The head structure 9 and the cap structure 10 are provided with water passageways 11 whereby the corresponding parts can be maintained cool. The cap 10 is secured to the head 9 by screws 12, and a bore 13 extends through the head 9 and cap 10 longitudinally thereof. It will be seen that the top of the head is formed with a low part at one side of the bore 13 and a high part at the other side, while the cap has its lower face formed with a depending part for engagement with the low side of the head and a higher part for engaging the high part of the head so that the major portion of the bore is in the head which acts to hold the rotor 16 in that part of the bore located in the head, when the cap is removed. Both the cap 10 and the head 9 are provided with longitudinally extending grooves 14 and within the bore are the bearings 15 which are interposed between the cap 10 and the head structure 9 and are located at equal spaced intervals along the rotor 16, separating the intake ports 17 from the exhaust ports 18.

In the slots 14 are the leaf springs 19 urging the packing elements 20 against the rotor 16. Extending through the head structure 9 to open each at one of its ends at the bore 13, and at its opposite end at the cylinder 6, are the intake

and exhaust ducts 21 and 22, and continuations of these ducts extend from the bore 13 through one side of the head, one of these passages being shown at 21' and these continuations communicate with the intake and exhaust manifolds 23 and 24 respectively. Each cylinder is equipped with a spark plug 25 and obviously before the fuel can pass from the duct 21, to the cylinder 6, the intake opening 17 of the rotor 16 must be registering therewith. As will be seen each cylinder is provided with an inlet passage and an exhaust passage and these two passages of each cylinder are controlled by a pair of the ports 17 and 18 of the rotary valve member.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

In an engine of the class described, a removable head having an inlet passage and an exhaust passage therein, for each cylinder of the engine, 85 said head having a longitudinally extending groove in its top surface which intersects the said passages, said head having a high part at one side of the groove and a low part at the opposite side whereby the groove is of greater cross 90 sectional area than a semi-circle a cap detachably connected to the top face of the head and having a groove in its lower face, forming with the first-mentioned groove a circular bore said cap having a depending part at one side of its groove contacting the low side of the head and a high part at the other side of its groove contacting the high part of the head, the walls of the bore having annular grooves therein spaced apart, each of the aforementioned passages entering the bore between a pair of said grooves, a rotor rotatably arranged in the bore and having annular rings thereon fitting in the grooves and said rotor having ports passing therethrough, 100 one between each pair of rings, said ports registering with the passages during the rotation of the rotor, said head having a longitudinally extending groove therein projecting out into the bottom of the first mentioned groove and the cap having a longitudinally extending groove therein 105 opening out into the top of the bore forming groove therein said longitudinal grooves intersecting the annular grooves, and a plurality of spring pressed strips in said longitudinal grooves in the cap and head for engaging the rotor 110 between the rings thereof.

JOSEPH EDWARD SMITH.
